UNITED STATES PATENT OFFICE

VICTOR MEYER, OF BROOKLYN, NEW YORK

HORSE BOOT

Application filed June 18, 1931. Serial No. 545,341.

The present invention relates to new and useful improvements in horse boots, and more particularly it pertains to protectors for the joints and limbs of animals, such as 5 horses and the like.

Heretofore, it has been the common practice to construct protectors for the limbs of horses from leather, and to secure them in position by means of straps and buckles.

10 Such devices have proven, however, to be difficult to maintain in support and protection to the limb upon which they are positioned which is due mainly to the stiffness of the leather particularly after the same has 15 been subjected to use. Furthermore, such devices do not afford the proper protection without the provision of pads of relatively soft material which have to be sewed or otherwise fastened to the protector.

20 It is an object of the present invention to provide a new and novel protecting device and support for the limbs of horses and similar animals which will have inherent tendencies to stay in the proper adjusted position in 25 which it is placed.

A further object of the invention resides in the provision of an elastic material preferably rubber for the purpose of making such 30 protecting devices, it having been found that rubber is one material which possesses the inherent ability to support and retain its position upon the limb of an animal.

A still further object of the invention resides in the provision of the character which 35 will provide highly effective cushioning effects and which will retain such ability to provide a cushion in use.

A still further object of the invention resides in a novel construction whereby the device 40 will be capable of permitting of free and easy movement of the joint of an animal by which it may be worn.

A still further object of the invention resides in the use of a new and novel material 45 for pads and protectors of the aforementioned type, which material permits of the attachment of securing devices such as straps, buckles and the like without injury thereto.

50 With the above and other objects in view, reference will be had to the accompanying

drawings forming a part of this application wherein;

Figure 1 is a view in elevation illustrating the inside of a horse's front leg showing a device constructed in accordance with one 55 form of the invention attached thereto,

Figure 2 is a view in elevation of the outside of a horse's leg illustrating that form of the device shown in Figure 1, Figure 2 being taken on a reduced scale, 60

Figure 3 is a horizontal sectional view taken on the line 3—3 of Figure 2,

Figure 4 is a similar view taken on the line 4—4 of Figure 2,

Figure 5 is a view in elevation of the outside of the front leg of a horse, showing a device of slightly modified form as attached thereto, 65

Figure 6 is a view in elevation of the outside of a horse's leg illustrating a still further modified form of the invention, 70

Figure 7 is a view in elevation of the inside of the front leg of a horse illustrating that form of the invention shown in Figure 6, 75

Figure 8 is a view in elevation illustrating the outside of the rear leg of a horse, showing a still further modified form of the invention, 80

Figure 9 is an inside view of the rear leg of a horse showing that form of the invention illustrated in Figure 8,

Figure 10 is a horizontal sectional view taken on the line 10—10 of Figure 9,

Figure 11 is a view in elevation of the inside of the rear leg of a horse illustrating a slightly modified form of the invention, 85

Figure 12 is a view in elevation showing a pad constructed in accordance with the present invention especially adapted for the protection of the pastern portion of the rear leg of a horse, 90

Figure 13 is a horizontal sectional view taken on the line 13—13 of Figure 12,

Figure 14 is a view in elevation of the rear leg of a horse showing a still further modified form of the invention, 95

Figure 15 is a view similar to Figure 14 showing still a further modified form of the invention,

Figure 16 is a view partly in section and 100

partly in elevation of that form of the invention illustrated in Figure 14.

Figure 17 is a view in rear elevation of that form of the device shown in Figure 14,

5 Figure 18 is a plan view of that form of the invention illustrated in Figures 14, 15 and 17, the device being spread or extended,

Figure 19 is a horizontal sectional view taken on the line 19—19 of Figure 16,

10 Figure 20 is a detail sectional view taken on an enlarged scale on the line 20—20 of Figure 18,

15 Figure 21 is a view in side elevation of the front leg of a horse showing a device constructed in accordance with the present invention for protecting the heels or quarters of a horse's foot,

20 Figure 22 is a view in elevation partly in section taken on an enlarged scale showing the device as employed for protecting the heels of a hoof,

25 Figure 23 is a plan view of the device illustrated in Figures 21 and 22, the same being spread or extended,

30 Figure 24 is a horizontal sectional view taken on the line 24—24 of Figure 22, and;

35 Figure 25 is a view in elevation illustrating a device as used in Figures 21 and 22 but of a slightly modified form.

40 In that form of the invention illustrated in Figures 1 to 5 inclusively, the invention is illustrated in the form of a pad for the protection of the shin portion of the front leg of a horse. The invention consists of a limb encircling body portion 30 which is composed of suitable soft flexible material such as rubber, and it is provided at the desired location with a relatively heavy or thickened portion 31 which provides the pad and which in the

45 present illustration of the invention is located upon the inside of the pad. The thickened portion 31 is preferably an integral portion of the main body portion 30 of the device, and in that form of the invention illustrated in Figures 1 to 4, the device is secured in position by means of straps 32 which engage with buckles 33 and which are adapted for interengagement upon the outside of the leg of a horse. The body portion 30 may be provided

50 with openings 34 and 35 to permit of free movement of the leg of a horse in action.

55 In Figure 5, there is shown a slightly modified form of the invention, and in this form of the invention the lower part of the main body portion is not adapted to be secured by straps as in the form illustrated in Figures 1 to 4, but is instead continuous or of a stocking like structure which may be stretched and slipped over the hoof of a horse

60 in positioning the device upon the leg thereof. This construction is designated 36 in the drawings, and it will be noted that at this point as well as at all other points, the edge of the device is thickened as designated at

65 37 to provide strength in all exposed edges.

In Figures 6 and 7 of the drawings, a device is illustrated for protecting the knee of the front leg of a horse, and in this form of the invention as illustrated in Figure 6, the device comprises a main body portion 40 of material similar to that heretofore described. The device is adapted to be wrapped around the leg of a horse, and secured together by means of straps and buckles illustrated at 41 in Figure 6, and the body portion 40 is provided with an opening 42 to accommodate the knee.

The body portion 40 is provided with a thickened portion 44 and 45 which form pads for the desired portions to be protected, and the opening 42 heretofore referred to permits of free knee movement of the horse.

In that form of the invention illustrated in Figures 8 to 11 inclusive, the invention is illustrated as a pad for the protection of a shin and hock of the rear leg of a horse, and in this form of the invention the device comprises a main body portion 50 which is adapted to be wrapped around the hind or rear leg of a horse and secured by means of a series of straps and buckles 51. The device is provided upon the inside portion with a thickened portion 52 and is provided with openings or the like 53 to accommodate the hock of the leg.

In this form of the invention as in other forms thereof, the device is formed from soft pliable material such as rubber and the thickened portion is an integral part of the main body portion thereof.

In Figure 11, there is shown a slightly modified structure in which the securing straps or buckles do not extend throughout the length of the pad, the upper portion such as 55 being of a stocking like structure which is adapted to be stretched and slipped over the hock of the leg to the position in which it is shown in Figure 11, the slit opening and buckle and strap securing means terminating at 56.

In Figures 12 and 13, the invention is illustrated in a pad for protecting the pastern of the leg, and in this form of the device, the body portion is designated 60 and is provided with a relatively thickened portion 61 which forms the protective pad. Straps such as 62 and buckles such as 63 are employed for securing the device in position, and one of said straps encircles the limb of the horse at a point immediately below the hock 64 the other set of straps encircling the hoof as best illustrated in Figure 12.

In that form of the invention illustrated in Figures 14 to 19 inclusive, the invention is set forth in the form of a pad for protecting the hock of a horse's leg and in this form of the invention, the device comprises a main body portion 70 which is molded and shaped to provide a seat or inwardly disposed hollow portion 71. This device is thickened

at this portion as indicated at 72, and is adapted to receive a removable cup shaped pad such as 73. In that form of the invention illustrated in Figures 14, 16, 17, 18 and 19, 5 the device is illustrated as secured in position by means of straps or the like 74 sewed or otherwise secured to the body portion 70 as at 75, and buckles 76. In this form of the invention the device is adapted to encircle the 10 limb of a horse, with the cupped pad receiving the hock of the limb and it is secured in position by engagement of the straps 74 with the buckles 76.

In Figure 15, however, this form of the 15 invention is illustrated as in the form of a stocking like structure which is stretched to pass over the hoof of the horse and after it is in position it is retained in such position by the inherent resiliency of the body portion. 20

In each form of the invention where the device is maintained in position, by means of buckles and straps, the straps are secured to the body portion of the device by sewing, 25 and in order to secure these straps by sewing, a construction such as illustrated in Figure 20 is preferred. In this figure, the body portion is designated at 80, and embedded therein there is a fabric 81. This fabric is preferably closer to one surface than the other of the body portion the surface to which it is the closest being that face to which the straps are secured. The straps are designated numerically as 82, and are secured to 30 the body portion by means of a line of stitching 83 of which there may be one or more and which stitching passes entirely through the straps, the body portion and the fabric embedded therein. 35

40 In Figures 21 to 25 inclusive, the invention is illustrated in the form of a pad for protecting the heels or quarters of a horse's foot or hoof and in this form of the invention, the device comprises a main body portion 90 having upwardly extending wing portions 91. A cut out portion 92 is provided and located in the body portion beneath the cut out portion, there are two cupped seats 93 which receive the heels or quarters of the hoof. As best illustrated in Figure 23, the cupped recesses 93 are formed in a thickened portion 95 and the thickened portion forms the pad for the heels which are designated 96 in the drawings. In this form of the invention the 45 device is secured in position by means of straps or the like 97 which engage buckles 98 as best illustrated in Figures 21 to 24 inclusive and when straps are in position upon the horse's hoof, the cupped recesses 93 will receive the heels of the hoof with the pad or thickened portion 95 positioned directly therebeneath and to the rear thereof, with the wing extensions 91 projecting upwardly in the direction of the hock. 55

60 65 In that form of the invention illustrated

in Figure 25, the straps and buckles 97 and 98 respectively are dispensed with and the entire protective device is of a continuous form and is adapted to be maintained in position merely through the inherent resiliency 70 of the material from which it is made.

From the foregoing it will be apparent that the present invention provides a new and improved form of protective pad and support for use upon the limbs and extremities 75 of limbs to prevent injury due to interference in action.

It is also to be understood that the present invention by reason of the fact that it employs relatively soft and resilient material, 80 provides a holding quality which secures the device in position without danger of accidental displacement thereof thus affording maximum protection and support at all times. 85

Having thus described the invention, what is claimed as new and what it is desired to secure by Letters Patent of the United States, is:

A boot for a part of a horse's leg comprising a leg encircling member, the leg contacting portions of which are formed of rubber and shaped to conform to the irregularities of the leg, the top and bottom portions of the boot having inside diameters which are slightly less than the corresponding outside diameters of the leg to which the boot is to be applied so as to exert a contracting and supporting pressure upon the leg when applied, said boot having an opening in its front portion intermediate the top and bottom portions, permitting protrusion of a portion of the joint during movement of the joint to which the boot is applied. 90

In testimony whereof I affix my signature.

VICTOR MEYER.
